[57] **ABSTRACT**

A flexible waveguide has an elongated hollow body having a non-circular cross section in which the ratio of the width of the wide side to the narrow side is less than 0.5. The body cross section includes an indentation extending along the longitudinal axis of the wave guide. The indentation is so shaped and the ratio of the width of the wave guide at the indented point to the width of the narrowest side is so small that interfering wave types do no occur.

BROADBAND FLEXIBLE WAVE GUIDES

BACKGROUND OF THE INVENTION

This invention relates to wave guides, and more particularly to a wave guide which is provided with at least one indentation for preventing the formation of interfering waves.

Most wave guides with rectangular cross section used in commercial installations are of a standard type which has a ratio of narrow to broad side width of 0.5. This ratio results in generally clear transmission with relatively low attenuation in the transmission range. For special purposes, such as the transmission of very broad frequency bands this standard cross section may be deviated from.

Some rectangular wave guides are formed with one or two metal strips extending along the longitudinal axis of the wave guide. These are called ridged wave guides and generally conduct a wider band width. It is difficult to manufacture these in desired lengths, or to make them flexible.

Among the objects of the present invention is the provision of a wave guide which may be used for the transmission of a relatively wide band width without producing an interfering second wave type (un wanted mode).

Other objects of the present invention include the provision of such a wave guide which can be made to desired lengths, and which can be made flexible.

SUMMARY OF THE INVENTION

Briefly stated, these and other objects of the invention are achieved by provision of a wave guide having a ratio of narrow side to broad side width of less than 0.5, and having an indentation formed so as to extend longitudinally along the wave guide body. The ratio of the width of the wave guide cross section at the indentation to the wave guide narrow side is made sufficiently small, and the indentation is appropriately shaped so that the occurrence of an interfering second wave type is prevented.

The wave guide may have two symmetrical indentations, may have planar wall portions in the area of the indentation, and may have a dielectric strip mounted within it between the indentations.

BRIEF DESCRIPTION OF THE DRAWINGS

FIG. 1 is a cross-sectional view through a wave guide formed according to one embodiment of the invention.

FIG. 2 is a cross-sectional view, similar to FIG. 1, of another embodiment of the present invention.

DESCRIPTION OF PREFERRED EMBODIMENTS

Referring now to FIG. 1, there is disclosed a wave guide according to the present invention. It includes a generally rectangular hollow body 7 having rounded corners. It has a wide side A and a narrow side B. Two symmetrical indentations 5 and 6 are formed which are extended toward each other and are integral with the broad or wide sides of the wall 2 of the rectangular body 7. The body has a cross sectional profile which is constant along the longitudinal axis of the body. The inner cross section of the body, as defined by the inner periphery 1 of wall 2, has a width a along its broad side, a width b at the widest part of its narrow side, and a width d between the indentations 5 and 6. Width d extends in the same general direction as the width b of the narrow side, but is less in dimension than the width b of the narrow side. The lines along which the greatest width b occurs are separated from each other by a distance c.

A dielectric strip 3 is mounted within the hollow body between the indentations 5 and 6. The hollow body can be wound on a drum or twisted. When this is done, the dielectric 3 mounted within the hollow body between the two indentations prevents contact between the opposite wave guide walls and limits the amount of deformation occurring in the area of a bend.

Another embodiment of the invention is schematically represented in FIG. 2. Corresponding parts of the structure of FIG. 2 have reference numerals corresponding to the similar parts of FIG. 1. The portions 4 of the wave guide wall in the region of the center of the indentations are parallel to each other. In this case the wall 2 of the hollow body is made with portions of greatest wall thickness e along the opposite narrow sides, rather than in the region of the indentations as in the FIG. 1 embodiment. This prevents displacement of the cross section and buckling when the wave guide is bent around a broad side a. As illustrated, the inner and outer peripheries of the cross-sectional profile of the wave guide wall 2 are continuous smooth curves without abrupt changes in direction. The wave guide of either embodiment is constructed as a seamless metal tube which is drawn to any desired length in a suitable machine. The wall thicknesses of the wave guides are selected so that a prescribed radius of curvature can be maintained when it is bent about a given radius of curvature or twisted through a given radius of curvature.

The ratio of d/b is maintained at such a level and the indentations are of an appropriate shape so that no interfering wave types arise.

The arrangement according to the present invention permits an extremely wide band width to be transmitted and prevents undesired occurrences of interfering wave types. One particularly advantageous use for these wave guides is the transmission of linearly polarized H_{10} (TE) waves over antenna feeder lines which lead to a listener-receiver, i.e. a receiver which intended to receive as wide a frequency band as possible from the antenna. With this type of device the attenuation of the wave guide is of lesser significance.

In order to determine the wave conducting properties, a number of tubes having the following dimensions were constructed:

TABLE I

Example 1	a	43.2 mm.
	b	21.2 mm.
	d	20.9 mm.
	d/a	0.48
	d/b	0.99
	b/a	0.49
Band Width Transmitted Without Interfering Side Waves — even in bendings and twisted sections —		
45		10 %
Example 2	a	40.0 mm.
	b	13 mm.
	d	10.5 mm.
	d/a	0.27
	d/b	0.8
	b/a	0.33
Band Width Transmitted Without Interfering Side Waves — even in bendings and twisted sections —		
50		10 %

A number of tubes of the type of FIG. 2 were constructed. These were then bent about one of their broad sides and twisted through torsional angles until they buckled. The results are set out below:

TABLE II

A	45.3 mm.
a	40 mm.
B	21 mm.
b	13 mm.
c	25 mm.
d	10.5 mm.
Min. Radius of Curvature	
Max. Torsional Angle about a guide length of one meter	
	150 mm.
	160°

Between the range of table I the attenuation of the wave guide is equal or better than that of standard type guides. If the ratio d/b is chosen to be smaller, the attenuation increases but the transmitted band width also increases. It is theoretically possible to enlarge the indentations 5 and 6 until they nearly reach each other in order to get a band width as great as possible.

We claim:

1. A twistable flexible wave guide of the type which can be wound on a drum and has a broad transmittable bandwidth comprising:
 an elongated relatively thin-walled flexible seamless metal tube having a constant noncircular cross-sectional profile along its longitudinal axis with the wall of said tube having a thickness which varies along its cross-sectional profile; the inner and outer peripheries of the cross-sectional profile of said wall of said tube being continuous smooth curves without abrupt changes in direction; the inner cross section of said tube, as defined by the inner periphery of the wall of said tube, having a wide side of width a and a narrow side of width b at the widest portion thereof with the ratio b/a being less than 0.5; said wall of said tube being shaped so that said inner cross section has a pair of symmetrical indentations which are opposite one another on the wide side thereof and which extend along the longitudinal axis of the tube, said inner cross section

5
 having a minimum narrow side width d between said indentations; said indentations being so shaped and the ratio d/b being so small as to provide a means for preventing the formation of interfering waves; and said cross-sectional profile of said wall of said tube having a maximum thickness along the opposite narrow sides thereof and a minimum thickness in the area of said indentations, whereby displacement of the inner cross section of the wave guide and buckling thereof is prevented when the wave guide is bent about the wide side thereof.

2. The wave guide of claim 1 wherein the portions of the wall of said hollow tube in the area of largest indentation are approximately planar.

3. The wave guide of claim 1 wherein said hollow tube is made of aluminum.

4. The wave guide of claim 1 in which the tube is shaped for transmission of linearly polarized H_{10} (TE) waves.
